UNITED STATES PATENT OFFICE.

JAMES G. GIBSON, OF PEORIA, ILLINOIS.

CHECK-ROWER.

SPECIFICATION forming part of Letters Patent No. 315,494, dated April 14, 1885.

Application filed October 6, 1884. (No model.)

To all whom it may concern:

Be it known that I, JAMES G. GIBSON, of Peoria, in the county of Peoria and State of Illinois, have invented an Improved Check-Rower; and I do hereby declare that the following is a full, clear, and exact description thereof, reference being had to the annexed drawings, making a part of this specification, in which like letters of reference refer to like parts, and in which—

Figure 1 represents a side elevation thereof; Fig. 2, a plan view of the same; Fig. 3, a sectional plan view at $x x$ in Fig. 1; Figs. 4 and 5, detail views.

This invention is in the line of check-rowers for corn-planters in which a hooked rod is adapted to be intermittently reciprocated through the medium of a tappet-wire and suitable mechanism, the movement of said rod being transmitted to the feed-slide of the planter through a lever and a block with which the hook of said rod engages.

My invention appertains, mainly, to automatic means whereby either rod may be detached from and the other connected to said block according to which side of the planter the tappet-wire may be upon.

In the drawings I show a portion of the transverse beam to which the check-rower mechanism is affixed, and show also the center piece and one end portion of the mechanism, the other end being exactly the same.

I will first describe the means whereby the hooked rod is reciprocated. R is the said hooked rod, and R' the similar rod running to the wire-operated mechanism at the other end of the transverse beam T. The hub A, having four radial bifurcated arms, A', projecting therefrom, is rigidly fastened to the gear-wheel B, which meshes with the one-half smaller pinion C. By the crank-pin C' one end of the rod R is pivotally attached to said pinion. The passage of the knots of the tappet-wire gives to the said four-armed hub an intermittent rotation, each movement of which is a quarter-turn. The wheel B fast to said hub being twice the circumference of the pinion C gives with each quarter-turn a semi-revolution to said pinion, and thence the desired reciprocation to the hooked rod R. The arms M, fixed to the end of the beam T, have friction-pulleys M', and fingers M' control the passage of

the tappet-wire in the correct place for the bifurcated arms A'.

To control the movements of the four-armed hub A, and stop the same at the end of each quarter-turn, I affix to and beneath the gear-wheel B a square block, E. Against the periphery of said block rests the head of the spring-impressed push-bar D, broadly slotted near the head thereof to make room for the bearings of the pinion C, as in Fig. 3. The spring f, by which said push-bar is kept against the box E, is confined in the semi-cylindrical cup F. Said spring presses against one end of said cup and against the shoulder d, formed on said push-bar. To increase or diminish the tension of the spring, said cup F is secured to the plate P by means of bolts passing through the longitudinally-slotted ears f' projecting from said cup F.

The bearings for the pinion C consist of the tubular lug C', projecting from the plate P. Said plate, which is cast as a part of the arms M, is secured to the beam T by means of the bolts a and C', which also serve as pivotal fastenings for the gear B and pinion C.

It is evident that when the block E is turned and the gear-wheel B fast thereto, the corners of said block displace the bar D and compress the spring f until one of said corners is directly between the two axes of the gear B and pinion C. As such corner passes said position the expelling force of the spring helps said block E on around until the head of the bar D rests flat against the next face of said block, and retains it there with more or less firmness, according to the strength of the spring.

My center movement consists of a block, H, having two holes, h, for receiving the hooked ends of the rods R R', ways J for permitting a longitudinal motion to said block, and a centrally-pivoted lever, G, for transmitting the movements of said block to the feed-slide of the planter. As a means whereby the said hooks are automatically connected to and detached from said block, I have devised the following:

Pivoted to a projecting portion, K, of the ways J is a three-armed device in the form of an inverted T. At the extremities of the cross-arms of said T are eyes n, through which pass the rods R R'. The height of said eyes

is so arranged that when one eye is depressed sufficiently to enable the hook of the rod held by said eye to enter a hole h of the block H , the other rod is raised by the other eye clear 5 above the block, as in Fig. 1. By rocking the T -piece N in one direction or the other, either hooked rod R may be engaged with the block H and the other rod disconnected therefrom. To make such change automatic with the movement of either four-armed hub A , I connect 10 a link, r , with the arm N' and each rod R R' . The connections for the links r with the rods R R' consist of double shoulders r^2 , the necks between which fit loosely in slots R^2 in the rods. The other ends of said links r are attached to the arm N' by means of eyes r' , formed at the ends of said links, and curved prongs n' , formed at the end of said arm N' . When the arm N' of the T -piece N is rocked 15 toward one rod, as R , the slot R^2 in said rod permits said rod to reciprocate back and forth without moving the link r . By this position of the arm N' the other link, r' , has its shouldered end brought against the near end 20 of the slot which it is in, and consequently when the rod, as R' , is retracted by the movement of its four-armed hub A the arm N' is pulled over toward it, it is lowered, the rod R is raised out of the hole h of the block H , and 25 its hook settles down into the other hole h of the block H . Now, each stroke of the rod R' reciprocates the block H and the feed-slide connected therewith.

When it is desired to detach one rod, R , 30 and connect the other rod with the block, the one to be disconnected must be left at its extreme stroke, so that the block H shall be at its farther position from the four-armed wheel A .

40 To retain the T -piece N firmly in either of its two positions, I form two notches, L L' , in the bearing-head K , Fig. 5, and adapt a small projection, m' , to rest in the same and either of the same, according as to which side the 45 T -piece is rocked. A spring, m^3 , abutting against the bearing-head K and the nut n^2 of the bolt, presses said projection into either one of said notches, L , and holds with more or less firmness the T -piece in either of its desired positions.

The lug m of the T -piece coming in contact with the ridges K' on the bearing-head K , serves as a stop to limit the rock in either direction of said T -piece.

What I claim as my invention, and for which I desire Letters Patent, is as follows:

1. The four-armed hub A , gear-wheel B , and square block E , all rigidly connected together on the same axis, in combination with the pinion C , the push-bar D , slotted to make 60 room for the bearings of said pinion, shoulder d on said push-bar, semi-cylindrical cup F , and spring f in said cup and about said bar, substantially as and for the purpose specified.

2. In combination with two rods adapted to 65 be intermittently reciprocated and a block connected to the feed-slide of a planter, a T -piece through eyes at the ends of the cross-arms of which pass said rods, and links attached to the third arm of said T -piece and 70 connected to said rods with fastenings that permit a limited play thereat, substantially as and for the purpose set forth.

3. The block H , having holes h therein, ways to permit longitudinal motion thereof, 75 and a lever for transmitting the movements of said block to the feed-slide of a corn-planter, in combination with the hooked rods R R' , adapted to be intermittently reciprocated, the T -piece N , pivoted to a bearing-head projecting from said ways, eyes n , at the ends of the cross-arms of said T -piece, through which pass said rods, and the links r , attached by the eyes n and prongs n' to the end of the arm N' , and secured at their other ends to said rods 85 by means of their double shoulders r^2 and slots R^2 in said rods, as and for the purpose specified.

4. In a check-rowing device of the kind herein described, the ways J , bearing-head K , 90 notches L L' , and ridges K' , in combination with the T -piece N , projection m' , lug m , bolt and nut m^2 , and spring m^3 , as set forth.

In testimony that I claim the foregoing invention I have hereunto set my hand this 29th 95 day of September, 1884.

JAMES G. GIBSON.
